CENTER LOCATING DEVICE

Filed Nov. 4, 1929

Henry F. Kieckhefer, INVENTOR
BY Victor J. Evans
H. S. ATTORNEY.

UNITED STATES PATENT OFFICE

HENRY F. KIECKHEAER, OF HAMMOND, INDIANA

CENTER LOCATING DEVICE

Application filed November 4, 1929. Serial No. 404,710.

This invention relates to certain novel improvements in a center locating device and has for its principal object the provision of an improved construction of this character which will be highly efficient in use and economical in manufacture.

The salient object of my invention is to provide a device of the above named character so constructed that it may be employed for locating the center on round stock such as is operated on in lathes and other analogous turning machines.

Another object of the invention is to provide a device of the above described character which will be particularly adapted for use in connection with so called round stock and as is well understood in the art this stock is supplied in standard sizes and I, therefore, provide an arrangement which will permit the employment of my device in connection with stock of various sizes.

A still further object of the invention is to provide a device of the above described character which will embody a movable member and which will have portions for locking sections of the movable member in a predetermined position relative to a marking member.

Other objects will appear hereinafter.

The invention consists in the novel combination and arrangement of parts to be hereinafter described and claimed.

The invention will be best understood by reference to the accompanying drawing, showing the preferred form of construction and in which:

Fig. 1 is an elevational view depicting a preferred form of construction for my invention in operating position;

Fig. 2 is an elevational view looking in at the bottom side of my device as depicted in Fig. 1;

Fig. 3 is a view looking in the opposite direction from Fig. 2;

Fig. 4 is a sectional view taken substantially on the line 4—4 on Fig. 3; and

Fig. 5 is a view taken substantially on the line 5—5 on Fig. 4.

In the accompanying drawing wherein I have illustrated a preferred form of con-

struction for my invention 10 generically indicates the main body portion of my improved tool. This main body portion includes a substantially circular head portion 11 from which a handle portion 12 is extended, the handle portion 12 being substantially circular in cross section and preferably being knurled as indicated at 13 to facilitate proper gripping thereof.

On the upper face of the circular portion 11, as viewed in Fig. 1, I provide a boss 14 which has a portion thereof disposed at the center of the head portion and which includes portions that extend radially from the center in diametrical opposition from the extent of the handle 12 and this is clearly illustrated in Fig. 4. Extending through substantially the midpoint of the circular head 11 and through the boss 14 is a tapped opening 15.

The movable member of my improved device is generically indicated by 16 and, as best illustrated in Fig. 2, this member 16 is circular in outline and is equal in diameter to the head 11. Extending through the member 16 at the midpoint thereof is a bore 17. A sleeve 18 is arranged in the bore 17 and a bolt 19 is passed through the sleeve 18 and a screw threadedly fitted into the opening 15, a washer 20 being disposed intermediate the head 21 of the bolt 19 and the face of the member 16. In this manner the member 16 is supported on the head 11 for rotative movement.

In the periphery of the member 16 at 85 spaced apart intervals semi-circular recesses 22 are provided. These semi-circular recesses are of different diameters corresponding to the diameters of standard round stock such as used in lathes and other turning machines. The centers of the semicircular recesses are disposed on the circumference of the member 16 and the head 11. If desired suitable indicia indicated by 23 may be provided in association with each of the recesses 22 to indicate the size of these recesses.

A circular opening 24 is provided at substantially the point of juncture between the handle 12 and the head 11 and the center line of this opening 24 passes through the cir-

cumference of the member 16 for a purpose to be set forth presently. In the opening 24 a rib 25 is provided in which rib there is an opening 26. A plunger 27 has a head 28 which is substantially conical and which has the apex thereof extended toward the face of the head 11 to which the member 16 is secured and this head 28 is disposed on one side of the rib 25. The plunger 27 has at the end thereof opposite the head 28 an enlarged head portion 29 and a reduced collar 30 is arranged intermediate the enlarged head portion 29 of the plunger 27. A coil spring 31 is disposed around the plunger 27 between the collar 30 and the rib 25 and acts to retain the head 28 within the opening 24.

In the member 16 on the face thereof disposed toward the head 11 a plurality of drilled openings 32 are provided. Each of the drilled openings 32 lies on a diametrical line drawn through the center of one of the recesses 22 and the center of the opening 17 and it is, therefore, manifest that for each of the recesses 22 there will be a diametrical- 20 ly disposed opening 32. The recesses 32 are disposed in circular formation about the opening 17.

A recess 33 extends into the boss 14 and the head 11 toward the face of the head 11 to which the member 16 is secured and an opening 34 extends between this recess 33 and said face of the member 11. A pin 35 is provided which is secured to a head 36 that is disposed in the recess 33. A stem 37 extends from the head 36 in a direction opposite to the pin 35 and is connected to a collar portion 38 exteriorly of which there is an enlarged head portion 39. The stem 37 is extended through a collar 40 that is retained 35 at the outer end of the recess 33 by the screw or other analogous securing device 41. A coil spring 42 is disposed about the stem 37 between the head 36 and the collar 40. The spring 42 acts on the head 36 to normally 40 force the pin 35 outwardly through the opening 34. The radius of the circle on which the openings 32 are disposed is equal to the distance between the center of the tapped opening 15 and the center of the recess 33 and it is, therefore, manifest that the pin 35 45 may be selectively disposed in one of the openings 32.

To facilitate construction, in the present instance, I have shown the handle 12 as being comprised of two portions, one of which is the boss 43 that extends from the head 11. The boss 43 has at the outer end thereof a tapped opening 44 into which the threaded stud 45 on the end of the handle member proper 46 is fitted but it is to be understood that the handle 12 might be made from one piece without departing from the purview of my invention. The portion of the boss 43 and the head 11 into which the opening 24 50 opens provides a relatively flat surface to be

known hereinafter as the abutment surface 47.

In use, a section of stock indicated by 48 is selected. This stock will be of a known diameter and in the present instance the stock 48 is of a diameter of one and one-fourth 70 inches. The recess 22 corresponding to this diameter is moved into a position in alignment with the abutment surface 47 and the pin 35 is inserted into the opening 32 that is in diametrical opposition to this selected recess 22. The stock 48 is then clamped in a vise 49 of standard construction in the manner illustrated in Fig. 1 wherein it will be seen that the stock 48 projects vertically from the vise 49. My improved tool is then gripped by the handle 12 and the end of the stock is disposed in engagement with the abutment surface 47 and the periphery of the stock 48 is engaged with the edge of the selected recess 22. Since this selected recess 22 has a radius equal to the radius of the stock 48, and since the center from which the recess 22 is defined lies on the circumference of the member 16, and since the apex of the conical head 28 is disposed on the center line of the opening 24, which center line passes through the circumference of the member 16, it is manifest that, when a blow is struck on the head portion 29, the conical member 28 will be forced outwardly against the action of the spring 31 and the apex thereof will be forced into the center of the stock 48 on the end thereof in engagement with the abutment surface 47. It is, therefore, apparent that the center of the stock 48 will be very effectively marked on one end thereof. By reversing the stock in the vise 49 the above described operation may be again carried out and it is, therefore, manifest that the center 90 will be marked on the other end of the stock which will greatly facilitate the centering of the stock in a lathe or other analogous turning device.

In order to position another recess 22 in alignment with the abutment surface 47 the head portion 39 is gripped and the pin 35 will, therefore, be retracted from the recess 32 in which it is disposed. This will permit the member 16 to be rotated relative to the head member 11 and when the selected recess 22 comes into alignment with the abutment surface 47 the pin 35 will enter the opening 32 that will have been moved into the above described diametrically opposed position.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claim.

Having thus described my invention what I claim as new and desire to protect by Letters Patent is:

A center locating device comprising a circular plate, a handle element extending therefrom, a disc rotatably mounted on said plate and having a plurality of recesses of different radii formed therein arranged about its circumferential periphery, said disc having 5 radially arranged indentations on the face thereof contiguous to the plate, a member slidably mounted in said plate and selectively engageable in the indentations to hold the plate and disc relatively immovable with respect to each other, and a punching element 10 slidably mounted in the handle on the periphery of the disc and adapted to strike the center point in the end of round stock selectively disposed in one of said recesses.

20 In testimony whereof I affix my signature.

HENRY F. KIECKHEAFER.
